SAID ROSENBERG ASSIGNOR TO SAID FRISCH

ADHESIVE APPLYING DEVICE

Application filed March 6, 1929. Serial No. 344,721.

This invention relates to an adhesive applying device, and an object is to provide a simple, inexpensive and practical means whereby an adhesive may be easily and expeditiously applied to various articles.

A further object is to provide means usable for the expeditious application of liquid adhesive onto surfaces of different contours.

A further detailed object is to provide means whereby two articles which are to be cemented together may be easily and simultaneously supplied with adhesive throughout their joint forming portions preparatory to placing them together.

A further object is to provide a machine including adhesive carriers, and means whereby adhesive of proper consistency may be easily supplied to said carriers.

A further object is to provide means which while useful in various relations is peculiarly useful in applying liquid adhesive onto the irregular joint forming edge surfaces of two part doll heads, doll babies, and like articles.

Other objects and aims of the invention, more or less specific than those referred to above, will be in part obvious and in part pointed out in the course of the following description of the elements, combinations, arrangements of parts and applications of principles constituting the invention; and the scope of protection contemplated will be indicated in the appended claims.

In the accompanying drawings which are to be taken as a part of this specification, and in which we have shown merely a preferred form of embodiment of the invention:—

Fig. 1 is a side elevational view, partly in section, of a machine constructed in accordance with this invention.

Fig. 2 is a side elevational view, partly in section on line II—II of Fig. 3, of the adhesive carriers appearing in Fig. 1, said carriers being in this instance of a type intended for use in applying adhesive to the two halves of a doll head, said halves being shown in different positions with respect to said carriers, and

Fig. 3 is a top plan view of the adhesive carriers shown in Fig. 2.

Since this invention is peculiarly adapted

for use in applying adhesive to the joint forming edge surfaces of the two halves of a doll head, it has been illustrated and will now be described in connection with this use, it being understood however that the essential features of the invention are nevertheless equally adapted for use in applying adhesive to numerous other articles as may suggest themselves from the nature of the invention.

Referring to the drawings for describing in detail the invention as illustrated therein the reference character L indicates a suitable container within which a quantity of liquid adhesive as 1 may be held. This container is shown as being supported within a boiler 2 beneath which is a heater 3 whereby the adhesive 1 may be kept at proper temperature and consistency as in the case of an ordinary glue pot. The boiler 2 is supported upon a frame 4 which carries a standard 5 within which is vertically mounted a slide rod 6 to the lower end of which is fixed the adhesive carriers G and H.

A lever 7 is pivotally mounted by its mid portion as at 8 upon the standard 5. One of its ends is pivotally connected as at 9 with the slide rod 6, and its other end is pivotally connected as at 10 with a link 11 which extends downwardly into pivotal connection as at 12 with a foot lever 13. The foot lever 13 is pivotally mounted as at 14 upon the frame 4 and a tension spring as 15 is connected thereto for urging it normally to an upper position against the stop 16 in which position the adhesive carriers are held normally submerged within the adhesive 1 as indicated by the full lines in Fig. 1.

Upon depression of the foot lever 13, movement thereof is transmitted through the link 11 and lever 7 to the slide rod for elevating the adhesive carriers out of the adhesive, to the position approximately as indicated by the dotted lines in Fig. 1.

The adhesive carriers are preferably formed of cast metal and when they are in their normal submerged condition they of course absorb heat from the adhesive so that when elevated out of the adhesive they retain heat sufficient to keep the adhesive at proper temperature for an ample period to 100

insure a proper consistency of the adhesive during the time while the members to which the adhesive is to be applied are being introduced thereto.

5 Any accumulation of congealed adhesive upon the carriers will be prevented by the normal submerged condition of the carriers, it being noted that during use the carriers will be moved into and out of submerged condition at frequent intervals.

The carriers G and H may be made up as two separate members connected together if desired, but for convenience are here shown as consisting of a single casting with the slide

15 rod 6 connected at their mid portion as by engaging within a socket 17 of the casting and being held by a set screw or the like as 18.

In order that the carriers are adapted to apply adhesive onto the edge surfaces as 19—

20 19 of the halves of a doll head as illustrated, said carriers are shown to each consist of a general ring shaped body portion 20 having an outer surface contour 21 corresponding to the contour of the adjacent outer surface of

25 the doll head part. An upwardly facing ledge 22 is provided upon this body upon which the doll head part may rest, said ledge being shaped longitudinally to conform with the edge surface of the doll head part and being slightly concaved so as to constitute an elongated pocket or channel 22 within which a quantity of the liquid adhesive may be retained when the carrier is lifted upwardly through the adhesive in the container L.

30 35 In the instance illustrated, the ledge 22 of the carriers G and H differ from each other in their longitudinal contour due to the fact that the ledge of the carrier G is required to follow the contour of the edge of the back 40 half member of the doll head while the ledge of carrier H follows the contour of the edge of the front half member of the doll head, the edges of the two half members of the head differing from each other, on account of the 45 presence of the ear projection of the head in the usual manner, in order to mate together in the finished head.

Adjacent to the ledge 22 each carrier is shaped to provide a wall 23 arranged inwardly of the ledge and following the general contour thereof adapted to stand interiorly of the doll head and in sufficiently close proximity to the inner surface of the doll head so that adhesive adhering to said 50 wall will be readily transferred in sufficient quantity to the adjacent inner wall surface of the head so that upon hardening it will constitute a desirable reinforcement of the material of the head adjacent the joint. The 55 adhesive thus applied onto the inner surface of the doll head adjacent the edge surface 19 will of course also have the effect of better insuring an ample quantity of adhesive at the joint in the finished doll head.

60 65 Using this device, an operator standing in

front of the machine illustrated in Fig. 1 and having the doll head halves one in each of his hands, merely presses the foot lever 13 so that the adhesive carriers G and H are lifted from the container L dripping with the adhesive 1.

70 75 He presses the two doll head halves onto their respective adhesive carriers G and H so that the joint forming edges of said halves rest upon the ledges 22, as indicated by the dotted lines 24 in Fig. 2. He may retain his hand grip of the two halves, and he then simply lifts them and moves their joint forming edges together as for instance by first bringing them to the position indicated by the dotted lines 25 and finally to the position indicated by the dotted lines 26 in Fig. 2, whereupon the assembled halves may be laid aside for drying in the usual manner. The carriers G and H may be lowered again into the

80 85 container L for receiving a fresh quantity of adhesive while the operator picks up another pair of doll head halves for repeating the operation.

90 95 Each time the carriers G and H are dipped into the adhesive the supply of adhesive within the concavity of the ledges 22, and upon the walls 23, is replenished, and the repeated dipping keeps the carriers at a proper temperature for preventing undesirable accumulations of adhesive thereon as above mentioned.

100 105 In order to facilitate the easy and convenient positioning of the doll head halves to their appointed places upon the ledges 22 of the adhesive carriers it may be desirable to provide suitable guide frames as 27 upon said carriers. These may have surfaces as 28 inclining toward the ledges adapted to be engaged by the doll head parts for guiding said parts to the ledges. These surfaces 28 may be made to project slightly outwardly beyond the wall surfaces 23 as shown so as to have a closer guiding engagement with the inner surfaces of the doll head parts and so as thus to definitely insure a certain amount of space between said wall surfaces 23 and the adjacent surfaces of the doll head parts suitable to permit the presence of an adequate quantity of adhesive upon said walls 23 for transferance to the walls of the doll head parts. Likelihood of the adhesive being wiped off when the doll head parts are lifted from the carriers is avoided by the same means.

110 115 It will be understood of course that the contour of the ledges 22, and of walls 23, their size, shape, etc., may be modified indefinitely to conform to the surfaces of different articles which are to receive adhesive therefrom, according to the different uses to which this invention may be put.

120 125 While it is herein stated that this invention is particularly adapted for the application of a liquid adhesive to various articles, nevertheless it will be understood that the essential features of the invention may be ap-

plicable to the placing of paint or the like of different colors on different parts of the articles if desired.

As many changes could be made in this construction without departing from the scope of the invention as defined in the following claims, it is intended that all matter contained in the above description, or shown in the accompanying drawings, shall be interpreted as illustrative only and not in a limiting sense.

Having thus described our invention, what we claim as new and desire to secure by Letters Patent is:—

1. An adhesive applying device by which to apply adhesive to the joint forming edge surfaces of the halves of a two part hollow doll head, said device comprising a container for containing a quantity of liquid adhesive, a pair of adhesive carriers mounted for movement into and out of submerged position within said container, each of said carriers consisting of a generally ring shaped body portion having an upwardly facing ledge thereon, said ledges of the two carriers being of a contour to conform to and receive the joint forming edge of one of the doll head parts respectively so that adhesive present upon said ledges when the carriers are moved upwardly from the adhesive in the container may be transferred to the joint forming edges of the respective doll head parts by the operation of placing said doll head parts with their joint forming edges upon said ledges, each of said carriers also having a wall surface adjacent to and following the contour of the mentioned ledge thereof adapted when the doll head parts are in position upon said ledges to stand adjacent the inner surfaces of said parts so that adhesive present upon said wall surfaces when the carriers are moved upwardly from the adhesive in the container may be transferred to the inner surfaces of the doll head parts adjacent the joint forming edges of said doll head parts, and means for manually moving the carriers into and out of submerged position.

2. An adhesive applying device by which to apply adhesive to the joint forming edge surfaces of the halves of a two part hollow doll head, said device comprising a container for containing a quantity of liquid adhesive, a pair of adhesive carriers mounted for movement into and out of submerged position within said container, each of said carriers consisting of a generally ring shaped body portion having an upwardly facing ledge thereon, said ledges of the two carriers being of a contour to conform to and receive the joint forming edge of one of the doll head parts respectively so that adhesive present upon said ledges when the carriers are moved upwardly from the adhesive in the container may be transferred to the joint forming edges of the respective doll head parts by the operation of placing said doll head parts with their joint forming edges upon said ledges, each of said carriers also having a wall surface adjacent to and following the contour of the mentioned ledge thereof adapted when the doll head parts are in position upon said ledges to stand adjacent the inner surfaces of said parts so that adhesive present upon said wall surfaces when the carriers are moved upwardly from the adhesive in the container may be transferred to the inner surfaces of the doll head parts adjacent the joint forming edges of said doll head parts, and means for manually moving the carriers into and out of submerged position.

3. An adhesive applying device by which to apply adhesive to the joint forming edge

surfaces of the halves of a two part hollow doll head, said device comprising a container for containing a quantity of liquid adhesive, a pair of adhesive carriers mounted for movement into and out of submerged position within said container, each of said carriers consisting of a generally ring shaped body portion having an upwardly facing ledge thereon, said ledges of the two carriers being of a contour to conform to and receive the joint forming edge of one of the doll head parts respectively so that adhesive present upon said ledges when the carriers are moved upwardly from the adhesive in the container may be transferred to the joint forming edges of the respective doll head parts by the operation of placing said doll head parts with their joint forming edges upon said ledges, each of said carriers also having a wall surface adjacent to and following the contour of the mentioned ledge thereof adapted when the doll head parts are in position upon said ledges to stand adjacent the inner surfaces of said parts so that adhesive present upon said wall surfaces when the carriers are moved upwardly from the adhesive in the container may be transferred to the inner surfaces of the doll head parts adjacent the joint forming edges of said doll head parts, and means for manually moving the carriers into and out of submerged position.

4. An adhesive applying device by which to apply adhesive to the joint forming edge surfaces of the halves of a two part hollow doll head, said device comprising a container for containing a quantity of liquid adhesive, a pair of adhesive carriers mounted for movement into and out of submerged position within said container, each of said carriers consisting of a generally ring shaped body portion having an upwardly facing ledge thereon, said ledges of the two carriers being of a contour to conform to and receive the joint forming edge of one of the doll head parts respectively so that adhesive present upon said ledges when the carriers are moved upwardly from the adhesive in the container may be transferred to the joint forming edges of the respective doll head parts by the operation of placing said doll head parts with their joint forming edges upon said ledges, each of said carriers also having a wall surface adjacent to and following the contour of the mentioned ledge thereof adapted when the doll head parts are in position upon said ledges to stand adjacent the inner surfaces of said parts so that adhesive present upon said wall surfaces when the carriers are moved upwardly from the adhesive in the container may be transferred to the inner surfaces of the doll head parts adjacent the joint forming edges of said doll head parts, guide means provided upon each carrier for

- engagement by the doll head parts to guide said parts into appointed relation with said ledges and wall surfaces, and means for manually moving the carriers into and out of submerged position.
5. An adhesive applying device by which to apply adhesive to the joint forming surfaces of the two parts of a two part article, said device comprising a container for containing a quantity of liquid adhesive, a pair of adhesive carriers mounted for movement into and out of submerged position within said container, means for so moving said carriers, said carriers each having an upwardly facing surface of a contour to conform to and receive the joint forming surface of one of the parts of the article so that adhesive present upon said surface when the carriers are moved upwardly from the adhesive in the container may be transferred to the joint forming surface of said part by the operation of placing said part with its joint forming surface resting upon the upwardly facing surface of the carrier, the adhesive carrying surface of the two carriers being counterparts one of the other and being arranged in opposing relation to each other in a manner such that the two parts of the article to be joined may be simultaneously manually lifted from the respective carriers and the adhesive carrying under-surfaces thereof brought together substantially as described.
6. An adhesive applying device by which to apply adhesive to joint forming portions of articles to be joined, said device comprising a container for containing a quantity of liquid adhesive, an adhesive carrier mounted for movement into and out of submerged position within the container, said carrier having an upwardly facing ledge thereon of a contour to conform to and receive the joint forming portion of said article so that adhesive present upon said ledge when the carrier is moved upwardly from the adhesive in the container may be transferred to the joint forming portion of the article by the operation of placing the article with its joint forming portion resting upon said ledge, said carrier also having a wall surface adjacent to and following the contour of the mentioned ledge extending upwardly from said ledge in position to stand in close proximity to wall surfaces of the article when the article is resting upon the ledge so that adhesive present upon the wall surface of the carrier will be transferred to the mentioned wall surface of the article; guide ribs provided upon said wall surface of the carrier spaced apart to be engaged by the mentioned wall surface of the article to guide the article in desired relationship to the ledge and to the mentioned wall surface of the carrier, and means for manually moving the carrier into and out of submerged position at will.
7. An adhesive applying device by which to apply adhesive to the joint forming edge surfaces of hollow articles to be joined, said device comprising a container for containing a quantity of liquid adhesive, an adhesive carrier mounted for movement into and out of submerged position within said container, means for so moving said carrier, said carrier being of general ring shape providing an upwardly facing edge surface of a contour to conform to and receive the joint forming edge of the article, said carrier having a part projecting upwardly at said centre providing relatively outwardly and downwardly inclining guide surfaces leading to said edge surface adapted to be engaged by the article for guiding the article to position upon said edge surface but said upwardly projecting part being open to permit passage of adhesive through said carrier.
8. An adhesive applying device by which to apply adhesive to the joint forming edge surfaces of hollow articles to be joined, said device comprising a container for containing a quantity of liquid adhesive, an adhesive carrier mounted for movement into and out of submerged position within said container, means for so moving said carrier, said carrier providing an upwardly facing surface of a contour to conform to and receive the joint forming edge of the article, said carrier having a wall surface intended to transmit adhesive to an inner wall surface of the article adjacent the joint forming edge of the article, and said carrier also having parts projecting upwardly therefrom adapted to extend into the hollow of the article providing relatively outwardly and downwardly inclining guide surfaces continuing as ribs across the mentioned wall surface of the carrier adapted to be engaged by the article for guiding the article to position upon said first mentioned surface of the carrier in spaced relation to said wall surface of the carrier.
- In testimony whereof we affix our signatures.
